UNITED STATES PATENT OFFICE.

WILLIAM SOCHEFSKY, OF NEW YORK, N. Y.

DECORATING WALL-HANGINGS AND OTHER FABRICS.

SPECIFICATION forming part of Letters Patent No. 320,409, dated June 16, 1885.

Application filed April 23, 1885. (Specimens.)

To all whom it may concern:

Be it known that I, WILLIAM SOCHEFSKY, a citizen of the United States, residing at New York, in the county and State of New York, have invented new and useful Improvements in Decorating Wall-Hangings and other Fabrics, of which the following is a specification.

This invention relates to a decorated fabric, 10 which consists of a stiffened and embossed textile material—such as muslin, cloth, or silk—coated with a solution of shellac, and finally painted with suitable coloring-matters.

In carrying out my invention I take a textile material—such as muslin—and treat the same 15 with a suitable sizing—such, for instance, as a solution of isinglass or gelatine—and then I expose the same to the action of embossing dies or rollers. The face of the embossed fabric is 20 then coated with a suitable liquid—such, for instance, as a solution of shellac—for the purpose of producing a smooth surface, and this surface is finally painted with suitable coloring-matters. For this purpose I can use oil- 25 colors, or alcoholic colors, or both combined. In some instances water-colors may be used.

The textile fabric which I use may be one, two, or three ply, according to the purpose for which the decorated fabric is to be used, and by following the above-described process I am 30 enabled to produce wall-hangings, coverings for furniture, and linings for carriages which have a close resemblance to leather, and which can be furnished at a greatly-reduced price as compared with the cost of similar 35 articles made from leather.

What I claim as new, and desire to secure by Letters Patent, is—

As a new article of manufacture, a decorated fabric composed of a stiffened and embossed 40 textile material—such as muslin—coated with a suitable liquid—such as a solution of shellac—and finally painted with suitable coloring-matters.

In testimony whereof I have hereunto set 45 my hand and seal in the presence of two subscribing witnesses.

WILLIAM SOCHEFSKY. [L. S.]

Witnesses:

W. HAUFF,

E. F. KASTENHUBER.
